US0D1053277S

(12) **United States Design Patent** (10) **Patent No.:** **US D1,053,277 S**
(45) **Date of Patent:** **** Dec. 3, 2024**

(54) **MODEL VEHICLE STEERING BLOCK**

(71) Applicant: **TRAXXAS, L.P.**, McKinney, TX (US)

(72) Inventors: **Kent Poteet**, Lucas, TX (US); **Otto Karl Allmendinger**, Rowlett, TX (US); **Adam Cole Ewing**, McKinney, TX (US); **Ross Martin**, Roanoke, TX (US); **Terry Soward**, Van Alstyne, TX (US)

(73) Assignee: **TRAXXAS, L.P.**, McKinney, TX (US)

(**) Term: **15 Years**

(21) Appl. No.: **29/886,327**

(22) Filed: **Mar. 7, 2023**

(51) **LOC (14) Cl.** **21-01**

(52) **U.S. Cl.**

USPC **D21/561**; D21/533; D21/483; D21/562

(58) **Field of Classification Search**

USPC D21/561, 562, 563, 565, 424, 495, 533

CPC A63H 17/262; A63H 19/18; B60G 7/003

(57) **CLAIM**

The ornamental design for a model vehicle steering block as shown and described.

DESCRIPTION

FIG. 1 is an upper, right, front perspective view of a model vehicle steering block showing our new design;

FIG. 2 is an upper, right, rear perspective view thereof;

FIG. 3 is a lower, left, front perspective view thereof;

FIG. 4 is a lower, left, rear perspective view thereof;

FIG. 5 is a rear elevation view thereof;

FIG. 6 is a front elevation view thereof;

FIG. 7 is a right side elevation view thereof;

FIG. 8 is a left side elevation view thereof;

FIG. 9 is an upper plan view thereof; and,

FIG. 10 is a lower plan view of the model vehicle steering block.

In the drawings, the broken lines illustrate portions of the model vehicle steering block that form no part of the claimed design.

1 Claim, 7 Drawing Sheets
